UNITED STATES PATENT OFFICE.

HOWARD L. KENNEDY, OF VAN WERT, OHIO, ASSIGNOR TO KENNEDY MANUFACTURING COMPANY, OF VAN WERT, OHIO, A CORPORATION OF INDIANA.

CARPENTER'S TOTE CASE.

Application filed March 11, 1926. Serial No. 93,897.

This invention relates to carpenter's tote cases, and more particularly to tote cases constructed of sheet metal.

An object of this invention is to provide a sheet metal carpenter's tote case of light weight and strong construction having convenient carrying means.

Another object of my invention is to provide a substantially weather proof carpenter's tote case.

A further object of this invention is to provide a carpenter's tote case having a cover, which case may be readily carried about whether said cover is in open or closed position.

Other objects of the invention will be apparent to those skilled in the art from the description of it hereinafter given.

In the drawings:

Figure 1 is a front elevation, partly in section, of a carpenter's tote case contemplated by my invention;

Fig. 2 is a top plan view, partly in section, of the tote case shown in Fig. 1;

Fig. 3 is an end elevation of the tote case; and

Fig. 4 is a vertical transverse section through the tote case.

The carpenter's tote case contemplated by my invention is shown in the drawings as including an open top container having a substantially rectangular bottom 1, side walls 2, 3 and end walls 4, 5. The upper portion 6 of the side wall 2 is shown as inclining upwardly and toward the side wall 3 to a relatively small linear extent. The upper portion 7 of the side wall 3 is shown as inclining upwardly and toward the opposed side wall 2 to a greater linear extent than the upper portion 6.

The bottom 1 and the side walls 2 and 3 are shown as formed of an integral piece of sheet metal. The end walls 4, 5, which are shown as contacting with substantially the entire end edges of said bottom and side walls, may be rigidly and permanently affixed to said bottom and side walls by interlocking the cooperating adjacent overlapped edges thereof, as shown at 8. The upper edge of the side wall portion 7 may be rolled as at 9 to provide a strong and convenient means to carry the tote case when the cover 10 is in open position. The overlapped

edges of the end walls 4, 5 may be cut away as at 11 to make the top opening of the tote case as large as possible for the convenience of the carpenter in placing or removing tools in or from said tote case. Hinges 12 may be affixed by suitable means, such as rivets, to the upper side wall portion 6 and to the cover 10, whereby said hinges are substantially concealed when the case is closed. The hinge pintles 13 preferably extend outwardly of the side wall 2. The cover 10, which preferably extends slightly outwardly of the end walls 4, 5, extends when in closed position over the rolled edge 9 and overlies a portion of the upper side wall 7. For strength, and protection from the weather, the cover 10 is provided with end flanges 14 which overlie the end walls 4, 5. The flanges 14 may be secured to the remainder of the cover 10 by suitably interlocked edges as shown at 15. The edge 16 of the cover 10 is shown as rolled about a rod 17 to provide rigidity and strength to the cover.

It will be seen by reference to Fig. 4 that the cover 10, when in open position, is adapted to depend along the side wall 2 as shown in the dotted lines. By this means the cover 10 is substantially out of the way and is not liable to bending or breakage when in open position and the tote box may then be readily carried about without inconvenience.

It will be noted that the distance between a pintle 13 and the edge 16 taken perpendicularly of the wall 2 is less than the height of the case up to the pintle 13, whereby the cover 10 when in open position does not extend to the bottom of the tote case and, therefore, does not interfere with the movement of the case. The cover 10 may be maintained in closed or locked relation as by means 18 with which may be associated a suitable lock.

To carry the tote box when the cover 10 is in closed position, strap supporting means 19 may be affixed to the end walls 4, 5 and between said means 19 an adjustable carrying strap 20 may be secured and adapted to extend when in carrying position over the top of the tote case. By means of the strap 20 the tote case may be carried by hand or over the shoulder as desired, according to the length of the strap. To prevent damage to sharp edged tools when dropped into the

tote case and to protect the bottom 1, an extra bottom 21, such as of wood veneer, may be disposed, if desired, within the tote case. Slotted cross members 22 may be disposed and affixed within the tote case adjacent to the bottom for the convenient disposition of saw blades and the like. Between the members 22 and one of the side walls may be provided a space 23 for the convenient disposition of a carpenter's level. For the support of a carpenter's square a slot 24 may be made in the upper wall portion 7.

It will be seen that I have provided a carpenter's tote case which is substantially weather proof and in which any contained tools are substantially protected.

It will further be noted that a tote case such as shown may be made of relatively thin metal and thereby be of light weight and yet, by suitable strengthening means, may be of sturdy, strong and rigid construction. It will be understood, of course, that the tote case contemplated by my invention may also be made of fiber or any other suitable material.

It will furthermore be seen that I have provided a carpenter's tote case having a cover, which case may be conveniently carried about whether the cover is in open or closed position.

It will also be seen that in my improved carpenter's tote case the cover when in open position is substantially out of the way and permits the box to be conveniently carried about.

To those skilled in the art many modifications of and widely differing embodiments and applications of my invention will suggest themselves, without departing from the spirit and scope thereof. My disclosures and the descriptions herein are purely illustrative and are not intended to be in any sense limiting.

What I claim is:

1. In a carpenter's tote case, in combination, a container of substantially rectangular section having a bottom, and side and end walls, the upper portion of one of said side walls inclining upwardly and toward the opposed side wall, the upper edge of said side wall being rolled to provide a strong convenient means to carry said case, said end walls contacting with substantially the entire end edges of said side walls.

2. In a carpenter's tote case provided with a cover, a sheet metal container having a bottom, end walls, and substantially parallel side walls, the upper portion of one of said side walls inclining upwardly and toward the opposed side wall, the upper edge of said side wall being rolled to provide a strong convenient means to carry said case when said cover is in open position, a cover for said container connected in hinged relation to the opposed side wall and overlying

the inclined portion of the first side wall, and means for carrying said tote case when said cover is in closed position.

3. In a carpenter's tote case provided with a cover, in combination, a sheet metal container having a bottom, and side and end walls, the upper portion of one of said side walls inclining upwardly and toward the opposed side wall, the upper edge of said first side wall being rolled to provide a strong convenient means to carry said case when said cover is in open position, a cover for said container connected in hinged relation to said opposed side wall and overlying the end walls and the inclined portion of said first side wall, and means for carrying said tote case when said cover is in closed position.

4. In a carpenter's tote case provided with a cover, in combination, a container having a bottom, and side and end walls, the upper portion of one of said side walls inclining upwardly and toward the opposed side wall, the upper edge of said side wall being rolled to provide a strong convenient means to carry said case when said cover is in open position, a cover for said container connected in hinged relation to said opposed side wall and overlying the inclined portion of said first side wall, said cover when in open position being adapted to depend along the adjacent side wall without extending to the bottom of the case, whereby said cover may not interfere with the movement of said case, and means for carrying said tote case when said cover is in closed position.

5. In a weather proof carpenter's tote case, in combination, an open sheet metal container of substantially rectangular section having a bottom, and side and end walls, the upper portion of one of said side walls inclining upwardly and toward the second side wall to a slight linear extent, the upper portion of the second side wall inclining upwardly and toward the first side wall to a greater linear extent, said end walls contacting with substantially the entire end edges of said side walls, a weather proof cover for said container connected in hinged relation to the inclined portion of said first side wall extending substantially from the vertical portion of said first side wall over the top of the opposed end walls and overlying the inclined portion of said second side

wall, end flanges on said cover overlying the adjacent end walls, said cover when in open position being adapted to depend along said first side wall without extending to the bottom of the case, whereby said cover may not interfere with the movement of said case, cooperative means to maintain said cover in closed relation, and means to carry said tote case.

6. A carpenter's tote case comprising, in combination, an open rectangular sheet

metal container having a bottom, and side and end walls, the upper portion of one of said side walls inclining upwardly and toward the opposed second side wall to a small 5 linear extent, the upper portion of said second side wall inclining upwardly and toward said first side wall to a greater linear extent, the upper edge of said second side wall being rolled to provide carrying means when 10 said case is open, said end walls contacting with substantially the entire end edges of said side walls, a cover connected in hinged relation to the upper inclined portion of said first side wall, extending over the tops of

the opposed end walls and overlying the 15 inclined portion of said second side wall, a flanged portion on each end of said cover overlying the adjacent end walls, said cover when in open position being adapted to depend along first side wall without extending 20 to the bottom of the case, securing means for maintaining said cover in closed position, and an adjustable carrying strap secured to said end walls and adapted to extend over the top of said case to provide 25 carrying means when the case is closed.

In testimony whereof I affix my signature.
HOWARD L. KENNEDY.
